UNITED STATES PATENT OFFICE.

WILLIAM T. MERSEREAU, OF ORANGE, NEW JERSEY.

DESIGN FOR A STAND FOR TEA-KETTLES.

SPECIFICATION forming part of Design No. 17,935, dated December 6, 1887.

Application filed November 10, 1887. Serial No. 254,835. Term of patent 3½ years.

To all whom it may concern:

Be it known that I, WILLIAM T. MERSEREAU, of Orange, Essex county, New Jersey, have invented a new Design for a Stand for a Tea-Kettle, of which the following is a specification.

The nature of my design is clearly shown in the accompanying drawing, to which reference is made; and it consists of a design for a stand for a tea-kettle. The upper portion of the stand is formed in the shape of the figure 5, and is supported by a circular rod ornamented by two balls, one placed at its base and the other near its upper end, while the rod itself is supported by the three curved legs, as shown.

Having now described my invention, I claim as new—

The design for a stand for a tea-kettle, the upper portion formed in the shape of the figure 5, supported by a circular rod ornamented by two balls, one placed at the base of the circular rod and the second one near its upper end, and the rod supported by the curved legs, as shown and described.

WILLIAM T. MERSEREAU.

In presence of—

WILLIAM V. H. HICKS,
A. SIDNEY DOANE.
